UNITED STATES PATENT OFFICE.

ALLEN A. BOWSER, OF FORT WAYNE, INDIANA.

ROTARY PUMP.

1,182,967.

Specification of Letters Patent. Patented May 16, 1916.

Application filed August 31, 1914. Serial No. 859,554.

To all whom it may concern:

Be it known that I, ALLEN A. BOWSER, a citizen of the United States, residing at Fort Wayne, in the county of Allen and State of Indiana, have invented certain new and useful Improvements in Rotary Pumps, of which the following is a specification.

This invention relates to a motor or pump comprising rotary members having teeth and recesses which coöperate with each other to form either a pump for liquids or a motor actuated by fluid under pressure. It may also be used as a meter for measuring the fluid passing through it and is so described in the present case, having a register actuating shaft in connection with it.

The principal object of the invention is to provide a pump or motor of this class which is simple in construction but effective and efficient in operation.

Among the objects of the invention are to provide a device of this class in which there is no dead center; to provide construction of two similar rotors movable in two similar bores with the minimum friction contact; and to provide a construction of this class in which there is no "packing" of the liquid by providing coöperating teeth in which there is always a passage from the contact surfaces thereof to the discharge side, thereby preventing back contact of the teeth and forming a noiseless construction.

For the attainment of these ends and the accomplishment of other new and useful objects as will appear, the invention consists in the features of novelty in the construction, combination and arrangement of the several parts generally shown in the accompanying drawings and described in the specifications, but more particularly pointed out in the appended claims.

In the accompanying drawings, Figure 1 is a sectional view of a motor constructed in accordance with the principles of my invention; Fig. 2 is a sectional view taken on the line 2—2 of Fig. 1; Fig. 3 is a sectional view taken on the line 3—3 of Fig. 2; Fig. 4 is a sectional view of a modified form of motor, and Fig. 5 is a sectional view of the modified form taken on the line 5—5 of Fig. 4.

One of the principal objections to fluid operated motors is that the teeth "pack" as the rotors are operated. By "pack" is meant the pocketing of the liquid by one of the teeth in the corresponding groove or

depression of the other rotor so that as both of the rotors rotate some of the liquid will be carried backward to the inlet side and this "packing" of the liquid by the teeth will not only cause the bearings of the rotors to become unduly worn, but also by the contact of the back of each tooth with its corresponding recess, will cause considerable noise and the maximum friction. Also the accuracy of the motor as a meter is impaired because of the fact that a certain quantity of the liquid which is "packed" will be carried from the exhaust side of the rotors to the inlet side.

By forming the teeth and the recesses of the rotors so that there will be a line of contact on one side of each tooth with a free passage therefrom to the discharge side, the friction and noise are eliminated, there is no "packing," and a fluid tight connection is made which is subject to less variation, leaking and backward movement of the fluid which acts upon the motor.

Referring more particularly to the drawings, a pair of rotors 7 and 8 are mounted upon shafts 9 and 10 respectively in a casing 11. A supplementary casing 12 is adapted to be secured to the casing 11 and inserted between the two casings is a plate 13 which confines the rotors in a chamber in the main casing 11 so that they fit closely therein. The plate 13 has an opening 14 at one side through which communication is made between the casings 11 and 12 through the chamber containing the rotors. The plate 13 is also provided with an opening 15 which makes communication between the casing 12 and a discharge passage 16 which, as seen in Fig. 2, has an outlet or discharge opening 17 at each end of the passage 16. An intake opening 18 is substantially in the same plane as the discharge openings and communicates with the chamber containing the rotors at one side thereof. The plate 13 forms a support for one end of both of the shafts 9 and 10 and is provided with bearings 19 through which the shafts pass. The other ends of the shafts 9 and 10 are mounted in bearings 20 seated in suitable recesses in the casing and accessible through openings therein in which are plugs 21.

Each rotor is formed with recesses 22 and teeth 23. Each tooth has a rounding forward contact face 24, a cutaway back face 25 and a curved extremity 26 which fits closely a circular recess of the casing in which the

rotor is operated. Each recess 22 is formed with a rounding contact face 27 and with a cutaway back face 28. Each tooth is adapted to make contact with the corresponding front face of the recess leaving a space around the tip of the tooth to the discharge side thereof. Each tooth and its recess are so formed that at all points of contact there is a passage from the contact point or line to the rear or discharge side of the casing. This is to prevent the "pack" of liquid by any one of the teeth in any one of the corresponding recesses, thus overcoming frictional resistance and preventing noise and undue wearing of the rotor pivots. Each rotor is secured to a shaft by means of a pin 29 extending through it and the shaft, or in any other suitable manner.

As shown in Fig. 3, the liquid enters the casing 11 through the opening 18 and by the pressure of the liquid the rotors are rotated in the direction of the arrows in Fig. 2, so that a certain amount of liquid is carried by the rotors from the inlet to the discharge side thereof and from the discharge side of the rotors the fluid is directed through the opening 14 of the plate 13 to the discharge opening.

As before explained, the rotors fit their respective parts of the casing closely and they contact on their pitch lines making a fluid tight connection. With this construction there can be no dead center for even though one of the rotors should reach such a position that it would be balanced by the incoming fluid the tooth of the other rotor, being further from its own center than the groove which receives the same pressure, would cause a rotation of the other rotor causing a continuous rotation of both of the rotors.

In order to keep the rotors in exact alignment each of the shafts 9 and 10 is provided with a gear 30 disposed in the casing 12 the teeth of which mesh and have a pitch line the same as the pitch line of the rotors. To one of these gears 30 is secured a worm geared member 31 which in turn is secured to one of the shafts 9 and to the other gear a member 32 is secured by means of bolts 33 which extend through large perforations 34 and into threaded openings in the gear 30. The bolts fit loosely in the perforations 34 for the purpose of permitting a slight adjustment of one of the gears 30 with respect to the other one. The member 32 is of course secured to the shaft 10. Meshing with the worm gear 31 is a gear 35 mounted on a shaft 36 which is for the purpose of driving the meter to which the motor is connected, or for driving any other device for which the motor is adapted. Opposite the other shaft 10 is a packing gland 37 through which a shaft 38 extends. At the inner end of the shaft 38 it is formed with a tooth 39

and the adjacent end of the shaft 10 and the member 32 are provided with a recess corresponding to the tooth 39 so that by their engagement as the shaft 38 is rotated in one direction the rotors may be rotated. For this purpose a crank or handle 41 is secured at the outer end of the shaft 38 and the purpose of this construction is to permit the manual rotation of the rotors to operate the motor as a pump, or to manually rotate the rotors for dislodging any foreign material from the rotors or to prevent them from sticking.

The path of the liquid from the intake to the discharge pipe is clearly seen in Fig. 2 in which it will also be observed that the intake apertures are in the casing 11. In the operation of such a motor it is necessary that the teeth make very close contact with their corresponding grooves and the means for the adjustment of the gears 30 with respect to each other is very essential.

In the modification shown by Figs. 4 and 5, a single casing 42 is provided in which rotors 8 and 9 are movable in the manner already described but with pitch line gears 43 secured directly to the rotors and mounted in the same chamber with them. A plate 44 forms a cover for the casing 42 and seats one end of the shafts 45 and 46 upon which the rotors are mounted, the other ends of the shafts being seated in the casing and one of the shafts 45 being provided with a worm 47 meshing directly with the gear 48 mounted upon a shaft 49 corresponding to the shaft 36 in the other form of motor. In this modified form there is an inlet 50 at one side of the casing with an outlet 51 at the other end of the casing.

Since there is no leakage in a motor of this kind, or so little leakage that it may be neglected, each rotation of the rotors is a measure of a certain quantity of liquid and if a counter is attached to one of the rotors it will record the passage of a certain amount of liquid through the motor.

What I claim is:

1. In a rotary motor, the combination of rotors each formed with teeth and corresponding recesses and each tooth being formed to contact with one side of the corresponding recess of the other rotor and to leave a free path in the recess around the end of the tooth, shafts upon which the rotors are mounted, and means to engage the rotors with each other, said means comprising a slotted blade member fixed to one shaft, another member loose on the shaft and a fastening bolt threaded in the member through the slot to vary the position of one of the members with respect to the other to hold each tooth in contact with the side of its corresponding recess.
2. In a rotary motor, the combination with parallel rotatable shafts, of rotors

180

- mounted thereon, each comprising teeth and coöperating recesses, gears having pitch lines corresponding to the rotors, means for securing one of the gears directly 5 to one of the shafts, a slotted blade fixed to the other shaft, and loose-fitting bolts threaded into the other gear through the slots of the blades for adjustably connecting the other gear to the other shaft whereby 10 the position of one rotor may be varied with respect to the other to take up wear and to maintain the front of each tooth in contact with the front end of its corresponding recess.
- 15 3. In a motor of the class described the combination with a casing having a chamber with circular walls, an inlet communicating with said chamber and having a discharge passage partitioned from said chamber, of an auxiliary casing, a plate between the casings with an aperture forming communication between the interiors of the two casings and another aperture forming communication between the auxiliary casing 20 and the discharge passage in the other casing, and coöperating toothed rotors mounted in the chamber of the first casing and rotated by the passage of fluid from the inlet to the discharge openings.
- 25 4. In a motor of the class described, the combination with a casing having an inlet and an outlet, of rotors each formed with teeth and corresponding recesses, each tooth and recess being formed so that the tooth engages one side of the recess only, shafts 35 in the casing to which the rotors are secured, a worm and gear connection with one of the shafts, a gear having the same pitch line as one of the rotors fixed to this shaft, a member with perforations fixed to the other 40 shaft, a gear with a pitch line the same as the other rotor meshing with the first named gear and formed with threaded perforations, and adjustable bolts extending loosely through the perforations in the member on 45 the last named shaft to vary the position of the rotor of this shaft with respect to the gear so that the rotors may be held in engagement and so that the front face of each tooth contacts with the front face of its corresponding recess.
- 50 In testimony whereof I have signed my name to this specification, in the presence of two subscribing witnesses, on this 17th day of August A. D. 1914.
